NORMAN R. PECHIN, OF PHILADELPHIA, PENNSYLVANIA.

KNITTING MACHINE.

Application filed February 24, 1923. Serial No. 620,986.

This invention relates to knitting machines and particularly to what is known as warp-motion knitting machines, and the principal object is to produce a machine of this type in which a flat arrangement of needles may be utilized to effect knitting of tubular material.

Another object is to produce novel movement of parts in such a machine.

Another object is to produce a simplified and efficient construction and operation.

With these and other objects in view the invention resides in certain novel construction and combination and arrangement of parts, the essential features of which are hereinafter fully described, are particularly pointed out in the appended claims, and are illustrated in the accompanying drawing, in which:—

Figure 1 is a vertical transverse sectional view of my machine, many of the parts being shown enlarged, and exaggerated as to size and relation, for the sake of clearness.

Figure 2 is a sectional view taken substantially on line 2—2 of Figure 1.

Figure 3 is a fragmentary horizontal section through the knitting machine.

Figure 4 is a fragmentary sectional view of the fabric formed by my machine.

Like characters of reference refer to like parts in all views.

Referring to the drawing in detail, 10 represents the main frame which may be of any suitable size, shape and construction to support the operating parts of the machine. Mounted in suitable bearings in the main frame 10 is the main operating shaft 11 which may be operated in any well known manner from any suitable source of power.

40 This main operating shaft carries a number of cams, each of which has its respective function to perform in the machine, the cams being so arranged and "set" on the shaft as to perform their several operations in positive timed order. Beginning at the left-side of the machine and passing along shaft 11 to the right side of the machine we encounter six cams, indicated respectively as

45 12, 13, 14, 15, 16 and 17. The first cam 12 controls the selvage thread layers in their movements; the second cam 13 controls the lateral movements of the rear needle plate;

the third and fourth cams 14 and 15 control the vertical movements of the needle lifting instrumentalities; the fifth cam 16 controls the lateral movements of the front needle plate and the sixth cam 17 controls the movements of the "side" thread layers. The specific connections of the various cams will hereinafter be fully described.

60 The operation of cams 14 and 15 in effecting vertical movements of the needle-lifting bars will first be considered. Referring particularly to the drawing, the numerals 18 and 19 indicate the needle-lifting bars which are provided with depending slide members 20 and 21 at the left and right and each passing down in close proximity to the faces of their respective operating cams 14 and 15. The slide members or bars 20 and 21 carry anti-friction rollers 22 which ride in the slots 23 of cams 14 and 15, the slots as illustrated being so formed as to reciprocate bars 18 and 19 twice at each revolution of shaft 11. The bars 20 and 21 70 are formed with enlarged lower ends 20' having oblong slots 24 which ride up and down on square blocks 25 threaded loosely on the shaft 11; and the upper ends of the bars 20 and 21 are bifurcated to form arms 26 which support the aforementioned needle-lifting bars 18 and 19.

75 We now come to the operation of the needle-bars, i. e., the bars against which the needles are secured and with which they move laterally. These bars, of which there are two are indicated respectively by the reference numerals 27 and 28. The bars are mounted to slide cross-wise of the machine in slots in the main frame 10. Extending 80 forwardly from the face of the front needle-bar 27, are four studs numbered respectively, 29, 30, 31 and 32, the first two being at the left-hand side of the plate, and the last two at the right-hand side. Similar 85 studs are arranged on rear plate 28 where they operate the same and effect the same results as do those on the front plate. Springs 33 and 34 secured to the needle-lifting bar 18 extend upwardly at the left and 90 right to cooperate with the studs in a manner to be presently set forth, and similar 95 springs co-operate with the studs of the rear plate 28.

In the present case, only six needles are shown, although it will be apparent when this description is fully read, that any number may be used and that they may be divided into any number of sections for concomitantly knitting a plurality of articles. However, for the present purposes, I show only the needles numbered 35, 36, 37, 38, 39, and 40, of which the first three are mounted on the needle-bar 27 and the others on the needle-bar 28.

The method of mounting is as follows:—

On the side of the needle-bars 27 and 28 are slide brackets 41, there being a pair of these brackets on each needle-bar. Slidable in the brackets of each needle-bar are a respective pair of clamping bars 42 and 43, the former number representing the lower bar of each pair, which rests on the respective needle-lifting bars 18 and 19. The needles are of the usual type and are provided with lugs or "heels" 44 which rest on the lower clamping bars 42 and are held in engagement by the aforementioned upper clamping bars 43. The needle-lifting bars 18 and 19 are provided with clamp hooks or fingers 45 which extend over the upper clamping bars 41 and hold the pairs of bars and needles for vertical movement with the needle-lifting bars while permitting sliding or horizontal movement with the needle-bars.

The sliding movement of the needle-bars is effected by means of links 46 connected to the upper ends of respective levers 47, the lower ends of which are provided with a roller 48 engaging in slots cut in the faces of the cams 13 and 16 which will in their operation cause the crosswise reciprocation of the needle-bars in two movements in each direction, the needle-bars being moved in reverse directions with relation to each other.

When the operation of shaft 11 begins, presuming the needle-bars to be in their extreme outward positions, the cams 13 and 16 first cause a movement of both bars inwardly, a distance equal to the distance between centers of needles; there is a short dwell, and then a second step of the same length inwardly; another slight dwell and the return or outward movements begin, the steps of the return movements being the direct reverse of the movements to the right. The entire cycle therefore comprising four steps of lateral movement of the needles, with four intervening dwells, one dwell in each direction being longer than the other so as to allow time for the stitch. Also in the operation, each yarn, after leaving some suitable source of supply passes through a thread guide 53. In fact there are two guides 53 and two strands of yarn, passing from the thread guides 53 to the needles, through the several needles and as the needles are operated the thread guides 53 move laterally

from each other and back again between the several needles, thereby feeding the yarn from the thread guides to the needles for the various courses. The thread guides 53 receive such movement due to the reciprocating movement of the links 74, which move in unison, and causes the thread guides to first separate then move toward each other and so on through the various courses of the threads of yarn.

While this movement of the needle-bars is controlled by cams 13 and 16, still, in a machine where such fine adjustments are necessary, other means must be provided to determine the throw of the needle-bars. That is what the studs 29, 30, 31, and 32 and springs 33 and 34 are provided for. The extreme left and right positions are determined by studs 29 and 32 contacting with the frame uprights 32' and the intermediate stops are determined by stops 30 and 31 contacting with the springs 33 and 34 respectively.

We now come to the thread layers, of which there are two kinds—the selvage layers and the side layers. The purpose of thread layers in any knitting machine is to carry the threads to the needles with which they co-operate, and the difference in the present case is that the selvage layers feed thread to needles of both plates (not at same time but alternately) whereas the side layers feed thread to needles of but one plate,—although it is to be clearly understood that there are side banks of thread layers for each of the two plates. In other words, the side layers co-operating with the needles of one side or bank do not co-operate with needles of the other bank, but each of the selvage layers co-operates with needles of both banks. Each thread layer (whether selvage or side) co-operates alternately with two needles, and each needle co-operates alternately with two thread layers.

Now considering the selvage thread layers first, two of these are shown in the present case and are numbered 49 and 50 respectively. (However, it is to be remembered that a larger number of selvage thread layers could be used when the machine is designed for turning out a plurality of articles simultaneously.) The selvage layer 49 is arranged at the left-hand end and feeds its thread to needles 35 and 38; and selvage layer 50 operates in conjunction with needles 37 and 40 at the right-hand end. Each of these layers feeds the thread first to one of its corresponding needles and then to the other. The selvage layers 49 and 50 are mounted for pivotal movement on through-bars or pivot rods 51 and 52, respectively. The ordinary thread layers now in use have round eyes formed in them through which the thread passes, but I have devised a new form of thread layer, by utilizing an elongated or oval eye 53 through which the

thread passes, which will very closely approximate in its minor diameter, the diameter of the thread and at the same time by having an elongated major axis will permit the free passage of the uneven spots in the thread, and gives room for the passage of filler in knitting shoe-laces, etc.

The selvage layers 49 and 50 are extended above their pivot rods 51 and 52 so as to form upper arms 54 and 55, respectively. These upper arms are slotted or bifurcated at their upper ends to receive cross-bars 56 and 57, respectively. These bars are a tight-fit in the notches and are mounted on the ends of arms 58 which extend outwardly and are pivotally secured to links 59 which extend downwardly through slots in the bed-plate of the frame 10, and have a pin and slot connection with arms 60 pivoted below the bed-plate and loosely connected at 61 to a vertically movable bar 62 which carries a roller or truck 63 operating in a slot 64 in the cam 12 to raise and lower the links 59 and rock the selvage layers from one position to another for carrying the thread about the needles.

Referring now to the side layers, there will be seen to be for the six needles used here, two of these side layers mounted on each of the two bars 51 and 52. The two side layers mounted on the bar 51 are shown at 65 and 66 respectively, and co-operate with the needles of the rear bank, layer 65 co-operating with needles 38 and 39 while layer 66 co-operates with needles 39 and 40. In like manner, layers 67 and 68 on bar 52 co-operate with needles 35 and 36, and 36 and 37, respectively. The side layers 65, 66, 67 and 68, are extended outwardly into arms 69 which are notched or bifurcated at their ends so as to co-operate with two bars 70 and 71 which have arms 72 and 73 pivoted on the upper ends of links 74, which links project downwardly through the bed-plate of the machine frame and are provided with arms 75, which arms are pivoted to each other and to a vertically moving bar 76 at 77. The vertically moving bar 76 carries a truck or anti-friction roller 78 which engages with a slot 79 in the aforesaid cam 17 at the extreme righthand of the machine. This cam is so shaped that upon each complete rotation of the operating shaft 11, the side thread layers will have been reciprocated twice so as to each effect threading of both of the needles with which it co-operates.

The cycle of operation of the operating shaft effects operation of the parts as follows: Cams 14 and 15 cause two vertical reciprocations of the needles 35-40, i. e., two stitches of all needles. Each of the layers therefore lays down two stitches or in other words, wraps its thread about two needles during the single operation. Each selvage

thread layer feeds to the respective end needles of each plate, and while one selvage layer is feeding to one of its co-operating needles, the other selvage layer is feeding the diagonally opposite needle. The side layers on each side feed those needles not being fed by a selvage layer. The two movements of the needle-bars in each direction, together with the concomitant movements of the thread layers wrap each thread around two needles during each complete cycle of operation. There are therefore two flat fabrics simultaneously knitted, and these are inter-knitted by the selvage layers so as to form a tubular fabric. By duplicating the arrangement of needles and layers, any number of articles may be simultaneously knitted.

While I have described what I deem to be the most desirable embodiment of my invention, it is obvious that many of the parts may be varied without in any way departing from the spirit of my invention, and I therefore do not limit myself to the exact details of construction herein shown nor to anything less than the whole of my invention limited only by the appended claims.

What I claim is:—

1. In a device of the class described, the combination of a pair of needle bars including a plurality of rectangular slots in the carrying frame for lateral reciprocating movement therein of said needle bars, a plurality of needles secured to and movable with said needle bars, a pair of vertically pivoted levers connected to said needle bars, an operating shaft, a pair of cams thereon for operating said pivoted levers in a horizontal reciprocating manner, a pair of needle lifting bars operatively associated with the needles on one of the needle bars, a pair of forked lifting studs secured to said needle lifting bars, a pair of eccentrically grooved face cams intermediate the ends of said shaft, the lower end of said forked studs provided with laterally extending pivoted rollers which engage in the grooves of said face cams, for effecting the vertical reciprocating movement of said needle lifting bars.

2. In a device of the class described, the combination of a pair of needle bars including a plurality of rectangular slots in the carrying frame for lateral reciprocating movement therein of said needle bars, a plurality of needles secured to and movable with said needle bars, a pair of vertically pivoted levers connected to said needle bars, an operating shaft, a pair of cams thereon for operating said pivoted levers in a horizontal reciprocating manner, a pair of needle lifting bars operatively associated with the needles on one of the needle bars, a pair of forked lifting studs secured to said needle lifting bars, a pair of eccentrically grooved face cams intermediate the ends of said

shaft, the lower end of said forked studs provided with laterally extending pivoted rollers which engage in the grooves of said face cams, for effecting the vertical reciprocating movement of said needle lifting bars, a concentrically grooved face cam at each end of said operating shaft for operating a

pair of pivoted connecting rods, and said rods operating a pair of vertical selvage thread and side thread layer bank rods adjustably pivoted adjacent the ends of said connecting rods. 10

In testimony whereof I affix my signature.

NORMAN R. PECHIN.
